NONREFILLABLE BOTTLE CLOSURE

Charles T. Alexander, Lynbrook, N. Y.

Application March 17, 1937, Serial No. 131,355

8 Claims. (Cl. 215—23)

This invention relates to new and useful improvements in non-refillable bottle closures.

The principal object of the invention is to provide a simple, efficient, durable, and economically manufactured mechanism which can be easily connected to the neck of any type of bottle to prevent it from being re-filled in an unauthorized manner.

A further object is to provide a device which can be securely and conveniently attached to the neck of any type of bottle without requiring a change in the construction of the bottle itself.

A further object is to provide in such a device a valve mechanism which will remain closed in substantially all positions of bottle inclination.

Yet a further object is to provide a valve mechanism controlled by a gravity-responsive, freely pivoted member for maintaining the valve in closed position irrespective of the bottle inclination.

Further and more specific objects, features, and advantages will more clearly appear from a consideration of the specification hereinafter when taken in connection with the accompanying drawing which illustrates a preferred form of the invention and which form a part of the specification.

Generally and briefly considered, the invention includes a bottle having a neck, preferably provided with crimping rings, to which a valve casing is connected, said casing having a dependent neck slidably fitting into the neck of the bottle. A looped member of resilient material is supported from said dependent neck and because of its resiliency can be pushed into the narrow bottle neck. The valve casing has a valve seat therein and encloses a valve adapted to bear against said seat. The valve is held against the seat in all positions of the bottle, except when the neck thereof is inclined downwardly to substantially the vertical by means of a gravity-responsive device disposed within the body of the bottle and connected to the valve. This valve seating element is preferably mounted freely and loosely on the above mentioned looped spring support which is connected directly to the valve casing so that the whole device is capable of being assembled as a unit separate from the bottle itself. The looped shape of the resilient support helps to hold the device on the neck of the bottle as will be seen from the drawing.

In the preferred form, the valve seating element takes the form of a weighted ball loosely swivelled on the resilient support and connected to the valve by means of a flexible connection

in such manner that the valve is seated except in positions of the bottle when it is inclined downwardly nearly to the vertical. Preferably the casing is provided with a wire mesh guard to prevent insertion of instruments for holding the valve open and is covered by a dispensing cap provided with small dispensing openings and fixedly crimped to the neck of the bottle so that it is impossible to tamper with the valve casing or to alter or impair it in any way. A suitable closing cap is provided over the dispensing cap to cover the dispensing openings when the bottle is not in use and to prevent leakage when the bottle is shipped or stored.

The preferred present form which the invention may assume is shown in the drawing of which,

Fig. 1 is a perspective view of the device shown in dispensing position;

Fig. 2 is a partial vertical section through the device; and,

Fig. 3 is a partial enlarged detail section showing the relation between the valve and its gravity-responsive seating device.

In the drawing, the present preferred form which the invention may assume comprises a bottle 10, shown as of rectangular cross section. The bottle has a neck 11 provided preferably with crimping rings 12. Disposed at the mouth of the neck 11 is a valve casing 13 having a dependent neck portion 14 extending into and snugly fitting the neck of the bottle. The casing is provided with an integrally formed bevelled valve seat 15 on which a valve 16 is adapted to be seated and guided by three legs 16'. To this valve 16 there is attached a connecting element preferably in the form of a flexible chain 17 which at its other end is connected to a gravity-responsive weighted element such as the ball 18. In particular the ball 18 may be provided with a slot 19 in which a pin 20 is disposed to grip the end of the chain 17 to permit adjustment of the length of the chain between the ball and the valve. Preferably the slot 19 is connected to a cross slot 21 through which the chain is threaded.

The ball is provided with a stem extension 22 with a much reduced portion 23 and an outer enlarged head 24 preferably with a bevelled surface adjacent the surface of the supporting member 25 which may take the form of a spring loop having an aperture 26 at its lower portion through which the reduced portion 23 of the stem 22 extends. The upper ends of the spring loop or supporting element 25 are connected to 55

the dependent extension 14 of the casing 13 in any suitable manner as by welding or soldering. It will be seen that the top portions of the spring loop are adapted to lie snugly against 5 the adjacent surface of the inner bottle wall and thus helps to keep the device in position on the bottle neck. Also the resilience of the loop 25 permits it to be compressed while it is pushed into and through the bottle neck to assume its 10 operative position the drawing shows.

The diameters of the aperture 26 and the reduced stem portion 23 are quite different so that the ball 18 is loosely swivelled in the spring 15 loop support member 25 and thus the ball will always tend to assume a position out of axial alignment with the plane of the support 25 except when the bottle is in an inverted position. In all positions other than the inverted, it is 20 obvious that the ball will cause a pull on the chain 17 which will keep the valve 16 seated. When the neck is well inclined downwardly the pull on the chain is reduced and the pressure of the contents of the bottle will unseat the valve and permit the flow of the liquid out of 25 the bottle. The plane of disposition of the spring loop within the body of the bottle is preferably transverse to the greater dimension of the body so that the plane of movement of the ball in its operation will be parallel to the 30 greater dimension of the bottle and thus the ball in its movement will not strike the sides of the bottle.

In order to protect the valve casing 13 and to prevent it from being accessible for unauthorized 35 tampering with the contents of the bottle, I have provided a protective shell or cup-shaped casing 27 which is disposed over the valve casing 13 and at its lower end is crimped or otherwise fixedly attached to the neck 11 of the bottle so that the 40 valve device is not only held firmly in place on the neck of the bottle but is also properly protected. The upper end of the protective casing 27 is closed except for oppositely disposed openings 28 one of which is shown in Figs. 1 and 2 45 and either of which may be used for dispensing while the other acts as an air vent. The upper outer surface of the casing 27 is preferably provided with threads 29 to receive a closing cap 30 the fit of which on the casing 27 is such as to 50 effectively close the openings 28 when the cap 30 is in place.

With the parts operatively assembled, it is only necessary to remove the cap 30 after which the bottle is tilted as shown in Fig. 1 in the plane 55 of the greater dimension. As the neck 11 is given a downward inclination, the point is finally reached where the ball 18 depends from its stem head 24 and will start to swing back from the position shown in Fig. 3 to that shown in Fig. 2 60 whereupon the tension on the chain 17 is lessened and the valve is allowed to open. This movement of the ball starts only when the neck has assumed a predetermined downward inclination substantially near the vertical. The entire 65 valve structure and related parts are assembled as one unit separate from the bottle and can be cooperatively associated therewith with ease and dispatch. The extension 14 can be quickly and snugly inserted into the bottle with the main 70 portion of the valve casing resting on the top of the neck. The spring loop 25 has been pushed through the neck and temporarily compresses as it passes through the neck but immediately springs back into the normal position shown in 75 Fig. 2 wherein its upper curved edges bear

against the adjacent wall of the bottle to help hold the device in position within and on the neck of the bottle. The protecting cap 27 is then slipped over the valve casing and crimped or swaged on to the neck 11. A screen wire 5 guard member 31 may be disposed in the valve casing over the valve 16 so as to prevent instruments from being slipped into the openings of the dispensing cup 27 to hold the valve off its seat and permit unauthorized filling of the bottle. 10

While the invention has been described in detail and with respect to a present preferred form thereof, it is not to be limited to such details and forms since many changes and modifications may be made in the invention without departing 15 from the spirit and scope of the invention in its broadest aspects. Hence it is desired to cover any and all forms and modifications of the invention which may come within the language or scope of any one or more of the appended 20 claims.

Having thus described my invention and pointed out the features which are new, what I claim is:—

1. In combination, a bottle having a neck, a 25 valve casing inserted into the neck of the bottle, a valve in said casing and adapted to open outwardly, a chain connected to said valve and extending into the bottle, a ball to which the chain is connected, a stem on said ball, a support to 30 which said stem is pivotally related, said support connected to the valve casing, the ball in response to gravity exerting a pull on the chain to hold the valve closed except in certain downwardly inclined positions of the bottle neck. 35

2. In combination, a bottle having a neck, a 40 valve casing inserted into the neck of the bottle, a valve in said casing and adapted to open outwardly, a chain connected to said valve and extending into the bottle, a ball to which the chain is connected, a stem on said ball, a support to 45 which said stem is pivotally related, said support connected to the valve casing, the ball in response to gravity exerting a pull on the chain to hold the valve closed except in predetermined downwardly inclined positions of the bottle neck, a protective casing fastened permanently to the neck of the bottle and covering the valve casing, said protective casing having opposed openings 50 therein for dispensing and air venting. 55

3. In combination, a bottle having a neck, a 60 valve casing inserted into the neck of the bottle, a valve in said casing and adapted to open outwardly, a chain connected to said valve and extending into the bottle, a ball to which the chain is connected, a stem on said ball, a spring loop 65 support connected at its outer ends to the valve casing and having an aperture in its lower portion through which the ball stem loosely passes and providing a loose swivelled connection for the ball, the upper curved portions of the loop adapted to bearing against the wall of the bottle and help hold the device in position, the resiliency of the loop permitting it to be pushed through the neck of the bottle while in assembled 70 condition.

4. In combination, a bottle having a neck, a 75 valve casing inserted into the neck of the bottle, a valve in said casing and adapted to open outwardly, a flexible element connected to said valve and extending into the bottle, a weighted element connected to said flexible element, a spring loop support disposed within the bottle and supporting the weighted element in a movable manner to provide a loose swivel support for said weighted 80 element. 85

- element, the upper curved portions of the loop adapted to bear against the wall of the bottle and help hold the loop in position, the resiliency of the loop permitting it to be pushed through the neck of the bottle while in assembled condition.
5. In combination, a bottle having a neck, a valve casing inserted into the neck of the bottle, a valve in said casing and adapted to open outwardly, a flexible element connected to said valve and extending into the bottle, a weighted element connected to said flexible element, a spring loop support connected at its outer ends to the valve casing, means on the spring loop support and connected to the weighted element whereby said element has pivotal movement thereon, the upper curved portions of the loop adapted to bear against the wall of the bottle and help hold the device in position, the resiliency of the loop permitting it to be pushed through the neck of the bottle while in assembled condition.
10. In combination, a bottle having a neck, a valve casing inserted into the neck of the bottle, a valve in said casing and adapted to open outwardly, a chain connected to said valve and extending into the bottle, a ball to which the chain is connected, a stem on said ball, a support to which said stem is pivotally related, said support connected to the valve casing, the ball in response to gravity exerting a pull on the chain to hold the valve closed except in predetermined downwardly inclined positions of the bottle neck, a protective casing fastened permanently to the neck of the bottle and covering the valve casing, said protective casing having opposed openings
15. therein for dispensing and air venting and said casing having screw threads around the periphery thereof and a threaded screw cap engaging said protective casing and which when in placement therewith closes the respective openings to prevent dispensing and air venting.
20. In combination, a bottle having a neck, a valve casing inserted into the neck of the bottle, a valve in said casing and adapted to open outwardly, a flexible element connected to said valve and extending into the bottle, a weighted element connected to said flexible element, a spring loop support connected at its outer ends to the valve casing, means on the spring loop support and connected to the weighted element whereby said element has pivotal movement thereon, the upper curved portions of the loop adapted to bear against the wall of the bottle and help hold the device in position, the resiliency of the loop permitting it to be pushed through the neck of the bottle while in assembled condition and a protective casing fastened permanently to the neck of the bottle and covering the valve casing, said protective casing having opposed openings therein for dispensing and air venting and said casing having screw threads around the periphery thereof and a threaded screw cap engaging said protective casing and which when in placement therewith closes the respective openings to prevent dispensing and air venting.
25. In combination, a bottle having a neck, a valve casing inserted into the neck of the bottle, a valve in said casing and adapted to open outwardly, a chain connected to said valve and extending into the bottle, a ball to which the chain is connected, a stem on said ball, a support to which said stem is pivotally related, said support connected to the valve casing, the ball in response to gravity exerting a pull on the chain to hold the valve closed except in predetermined downwardly inclined positions of the bottle neck, a protective casing fastened permanently to the neck of the bottle and covering the valve casing, said protective casing having opposed openings
30. therein for dispensing and air venting and said casing having screw threads around the periphery thereof and a threaded screw cap engaging said protective casing and which when in placement therewith closes the respective openings to prevent dispensing and air venting.
35. In combination, a bottle having a neck, a valve casing inserted into the neck of the bottle, a valve in said casing and adapted to open outwardly, a flexible element connected to said valve and extending into the bottle, a weighted element connected to said flexible element, a spring loop support connected at its outer ends to the valve casing, means on the spring loop support and connected to the weighted element whereby said element has pivotal movement thereon, the upper curved portions of the loop adapted to bear against the wall of the bottle and help hold the device in position, the resiliency of the loop permitting it to be pushed through the neck of the bottle while in assembled condition and a protective casing fastened permanently to the neck of the bottle and covering the valve casing, said protective casing having opposed openings therein for dispensing and air venting and said casing having screw threads around the periphery thereof and a threaded screw cap engaging said protective casing and which when in placement therewith closes the respective openings to prevent dispensing and air venting.
40. In combination, a bottle having a neck, a valve casing inserted into the neck of the bottle, a valve in said casing and adapted to open outwardly, a flexible element connected to said valve and extending into the bottle, a weighted element connected to said flexible element, a spring loop support connected at its outer ends to the valve casing, means on the spring loop support and connected to the weighted element whereby said element has pivotal movement thereon, the upper curved portions of the loop adapted to bear against the wall of the bottle and help hold the device in position, the resiliency of the loop permitting it to be pushed through the neck of the bottle while in assembled condition and a protective casing fastened permanently to the neck of the bottle and covering the valve casing, said protective casing having opposed openings therein for dispensing and air venting and said casing having screw threads around the periphery thereof and a threaded screw cap engaging said protective casing and which when in placement therewith closes the respective openings to prevent dispensing and air venting.

CHARLES T. ALEXANDER.
